UNITED STATES PATENT OFFICE.

JOSEPH DE LIPKOWSKI, OF PARIS, FRANCE.

ACCELERATOR FOR AIR-BRAKES.

1,083,891.

Specification of Letters Patent.

Patented Jan. 6, 1914.

Original application filed December 13, 1911, Serial No. 665,552. Divided and this application filed June 20, 1913. Serial No. 774,834.

To all whom it may concern:

Be it known that I, JOSEPH DE LIPKOWSKI, a subject of the Emperor of Russia, and a resident of Paris, France, have invented a 5 certain new and Improved Accelerator for Air-Brakes, of which the following is a specification.

The present invention relates to accelerators for air brakes and particularly to brakes 10 of the type disclosed in my copending application Serial Number 665,552 of which the present application is a division.

The object of my invention is to provide a simple and efficient accelerator of this type, 15 having the characteristics hereinafter pointed out.

In the accompanying drawing, Figure 1 is a longitudinal section through an accelerator in which my invention is embodied in 20 one form; Fig. 2 is a similar view of a modified construction provided with a cutting-out cock; Figs. 3 to 6 are sections through this cock showing its position respectively, when operating the brake without the ac- 25 celerator, when cutting out brake and ac- celerator, when operating the brake with the accelerator, when operating the accelerator with the brake cut out.

The present accelerator in the form here 30 shown comprises a valve L held to its seat by a spring M and mounted on the end of a spindle carrying, spaced apart, the two pistons P¹, P², which slide in their respective guide ways in the casing. Two diaphragms 35 L¹, L², of unequal diameter, are also carried by the valve stem, and the smaller dia- phragm L², which is exposed to atmospheric pressure, is of such size that it balances the atmospheric pressure upon the lower face 40 of the valve L. The compressed air from the pipe N, N, passes through the piston P¹ by way of the small orifice p, and fills the space O located between the two pistons and form- 45 ing a pressure reservoir. Inasmuch as both piston P² and valve L are subject to atmos- pheric pressure on their outer faces and to the pressure of the air of the train pipe on their inner faces, the apparatus is normally 50 in equilibrium.

When the driver applies the air brake 55 gradually in the ordinary way, the fall of pressure produced in the train pipe is slight and gradual enough for the compressed air inclosed between the two pistons P¹ and P² to pass into the train-pipe through the orifice

p without moving the piston P¹. But in the case of a sudden or emergency stoppage, the fall of pressure produced in the train-pipe by the driver is so rapid that the air in the accelerator reservoir O on the first carriage 60 cannot at once establish equilibrium on both sides of the diaphragm L² through the ori- fice p. The piston P¹ is, therefore, moved downward, the valve L is opened quickly and the train pipe thus emptied. The great 65 fall of pressure thus made in the train pipe spreads almost instantly from one accelera- tor to the other and the action of the brakes is rendered extremely rapid. After the ac- celerated braking the valve L of the accelera- 70 tor closes again under the action of the spring M and the accelerator no longer in- fluences the usual gradual braking action.

In order to cut out the accelerator there is provided a small bolt or key (not shown 75 on the drawings) which allows the valve L to be locked.

The accelerator can be fitted, (1.) To a wagon, not braked, but simply supplied with a train-pipe. (2.) To a braked wagon 80 by placing the accelerator on the train- pipe. (3.) To a braked wagon by fixing the accelerator directly on the air distributer. In this case the accelerator is supplied with a union or coupling which is fixed on a simi- 85 lar union on the distributer.

The modification of the accelerator shown in Fig. 2 differs from the preceding form only by the addition of a special cut-out cock. The action of this accelerator is the 90 same as that which has just been described.

The cut-out cock can assume any one of the four positions shown in Figs. 3, 4, 5 and 6. In the position shown in Fig. 3, the cock connects the train-pipe N with the pipe 95 N¹ leading to the distributer. In the position shown in Fig. 4, the brake and the ac- celerator are completely cut-off from the train pipe N. In the position shown in Fig. 5, the brake and the accelerator are both 100 operatively connected to the train-pipe. These three positions are the same as in the Westinghouse brake. In the position shown in Fig. 6 the accelerator alone is op- 105 erative and the brake is cut out. This po- sition, which is not found in any other brake arrangement, has the great advantage of retaining the accelerator in case damage to the brake or valve gear necessitates cut- ting out the brake.

The two diaphragms of the accelerator are mounted on malleable iron pistons separately secured on the central stem, each by a single nut. This permits each piston to be taken off separately for inspection or replacement, without dismounting the whole apparatus.

I claim as my invention:—

1. An accelerator for compressed air brakes, comprising an accelerator valve opening to atmosphere and a stem therefor, pistons spaced apart on said stem, diaphragms of different diameter carried by said pistons, the smaller diaphragm being exposed on one side to atmosphere and being of a size to equalize the atmospheric pressure on one face of the accelerator valve.
- 10 2. An accelerator for compressed air

brakes, comprising an accelerator valve opening to atmosphere and a stem therefor, independent pistons spaced apart on said stem, diaphragms of different diameter carried by said pistons and each mounted thereon by a single nut, the smaller diaphragm being exposed to air pressure and being of a size to equalize the atmospheric pressure 20 on one face of the accelerator valve.

In testimony whereof I have signed my name to this specification, in the presence of two subscribing witnesses.

JOSEPH DE LIPKOWSKI.
